BENDING TOOL

Joseph Sunnen, Kirkwood, Mo.

Application May 15, 1933, Serial No. 671,088

1 Claim. (Cl. 81—15)

My invention has relation to improvements in bending tools and it consists in the novel features of construction more fully set forth in the specification and pointed out in the claim.

5 The invention is more particularly directed to tools for bending connecting rods of internal combustion engines for the purpose of restoring the proper alignment of the engine piston and crank shaft.

10 The principal object of the invention is to provide a bending tool that may be applied to the piston pins holding the piston and connecting rod in assembled relation. A further object of the invention is to provide a bending tool that is instantly adjustable for operations on pistons of varying sizes. Further objects are to provide a tool for the purpose stated that is simple and rigid in construction; one that is easily operated; and one possessing further and other advantages 20 better apparent from a detailed description of the invention in connection with the accompanying drawing, in which:

Figure 1 is a side elevation of my improved bending tool shown applied to an assembled connecting rod and piston for the purpose of restoring the correct alignment thereof; Fig. 2 is a top plan of my improved bending tool; Fig. 3 is a top plan of a connecting rod and piston assembly showing the bending tool applied thereto; and Fig. 4 is a top plan of a modified form of bending tool.

It is a matter of common knowledge among automobile mechanics that for various reasons pistons will get out of alignment with the crank shaft which serves to actuate the piston. This disalignment may be caused by either a bent or twisted connecting rod, in the first instance causing the piston to teeter in the cylinder and eventually producing a severe piston slap, and in the second instance effecting a rotation from its normal position of the piston in the cylinder so that the thrust thereon will come in a place at which the piston is not designed to receive said thrust.

Skilled mechanics readily perceive the above mentioned defects and seek to correct them by removing the connecting rod and straightening the same by twisting and bending operations applied directly to the connecting rod. However, after the connecting rod has been straightened it is not necessarily true that the piston will be properly aligned, which must be determined by the mechanic by trial and retrial. My improved bending tool is applied directly to the piston pins holding the piston and connecting rod in assembled relation so that the bending operations

on the connecting rod are governed by the degree of disalignment of the piston and are performed for the purpose of restoring the correct alignment thereof irrespective of whether the connecting rod is perfectly straight or not. This is as it should be because, as stated above, the purpose of straightening the connecting rod is to restore the alignment of the piston and not merely to have a straight connecting rod.

This comparatively simple and direct operation 10 of my improved bending tool will be more clearly understood by referring to the drawing, in which P represents a piston and R a connecting rod assembled by means of a piston or wrist pin W. We will assume that the piston P is not 15 properly lined up with the engine crank shaft, the center line of which is indicated by CL in Fig. 1. After having determined the direction and the amount of the disalignment the mechanic clamps the connecting rod R between the 20 jaws J, J of a suitable device preparatory to bending the connecting rod R with my improved bending tool for the purpose of restoring correct piston alignment. The bending tool comprises a U-shaped yoke 1, preferably formed of a hollow 25 casting of rectangular cross section, in the walls of the sides 2, 2 of which are openings o, o in which are slidably mounted bars 3, 3. Each of the bars 3 passes entirely through the side 2 of the yoke in which it is mounted and has its inner end 4 tapered as shown so as to readily enter the hollow wrist pin W. A stop pin 5 is passed through the inner end of each bar 3 immediately behind the tapered end 4, and a knurled portion 6 is provided on the outer end of each bar 3 to 30 facilitate the gripping thereof by the operator. In order to apply the bending tool to the assembled piston P and connecting rod R the operator grasps the knurled portions 6, 6 of the bars 3, 3 and slides the bars outwardly far enough 35 so that the tapered ends 4, 4 thereof may be inserted into the ends of the wrist pin W. If he has previously determined that the disalignment has caused a rotation of the wrist pin in a vertical plane (as indicated by the center lines x 40 and y showing such rotation greatly exaggerated in Fig. 1) he applies the necessary amount of force to the bars 3, 3 to rotate the wrist pin in a direction to correct such disalignment. Of course, in this rotating movement the connecting 45 rod R will undergo a bending movement. If, on the other hand, the disalignment is due to a twist in the connecting rod R the wrist pin will have been rotated in a horizontal plane (as indicated in Fig. 3 by the center lines x', y' greatly 50

exaggerated) and may be restored to its proper position by a counter rotation by the application of the necessary force to the bars 3, 3.

From the foregoing it is apparent that by means of my improved bending tool the connecting rod R may be bent or twisted, or both if necessary, in order to restore correct alinement to the piston P and greater accuracy may be obtained because the bending force is applied directly to the piston, the object of the refinement.

In Fig. 4 I show a modification of the bending tool wherein only one bending bar 10 is used. Instead of the oppositely disposed bending bar of the main form I secure a tapered stud 11 into the yoke 12. As in the main form, however, the bar 10 and stud 11 are in axial alinement and

the bar 10 is slidably mounted in the yoke 12 for the purpose of adjustment.

Having described my invention, I claim:

A connecting rod bending tool comprising a U-shaped yoke, the sides of said yoke having circular openings near their ends in axial alinement with each other, a pair of bars carried by said yoke in opposing relation, each bar having bearing in one of said openings and being slidable therein, each bar being circular in cross section and tapered at one end to readily enter a hollow wrist pin and having means thereon to limit sliding movement of the bar in one direction and said bars being of substantial length to serve as operating handles for the tool.

JOSEPH SUNNEN.
